[57] CLAIM

The ornamental design for a electronic game housing, as shown and described.

DESCRIPTION

FIG. 1 is an elevational perspective view of a electronic game housing showing our new design;

FIG. 2 is a front view thereof;

FIG. 3 is a right side view thereof, the left side being a mirror image thereof;

FIG. 4 is a rear view thereof;

FIG. 5 is a top plan view thereof;

FIG. 6 is a bottom view thereof; and,

FIG. 7 is an auxiliary view viewed along line 7—7 of FIG. 3.
